UNITED STATES PATENT OFFICE.

JACOB KUHN AND JOHN A. GUILER, OF CONNELLSVILLE, PENNSYLVANIA.

PROJECTILE.

1,288,047.

Specification of Letters Patent. Patented Dec. 17, 1918.

Application filed August 26, 1918. Serial No. 251,522.

To all whom it may concern:

Be it known that we, JACOB KUHN and JOHN A. GUILER, citizens of the United States, and residents of Connellsville, in the county of Fayette and State of Pennsylvania, have invented certain new and useful Improvements in Projectiles, of which the following is a specification.

This invention relates to projectiles, and 10 an object of the invention is to provide a projectile construction including means for preventing the cutting of the rifling of the gun barrel through which the projectile is forced.

15 More specifically, the invention comprehends the provision of a projectile provided with a plurality of circumferentially spaced longitudinally extending ribs or strips, detachably carried by the body of the projectile and formed of a relatively soft metal, which may be gripped or will bite into the 20 rifle of the gun barrel, without cutting the rifling of the gun barrel.

Other objects of the invention will appear 25 in the following detailed description, taken in connection with the accompanying drawing, forming a part of this specification, and in which drawing:

Figure 1 is a side elevation of a projectile 30 constructed in accordance with this invention.

Fig. 2 is a fragmentary longitudinal section through the projectile.

Fig. 3 is a transverse section taken on the 35 line 3—3 of Fig. 1.

Referring more particularly to the drawing, 1 indicates the projectile, which may be a shrapnel shell, rifle bullet, solid projectile, or any of the many types now in use. The 40 projectile 1 is provided with a plurality of circumferentially spaced longitudinally extending dovetail recesses 2, the forward ends of which terminate in substantially circular recesses 3 near the nose or pointed end of 45 the projectile. Strips 3 of soft metal, such as copper or the like, are inserted in the recesses 2, the said strips being dove-tail in cross section for fitting snugly within the recesses so as to prevent the strips from 50 springing therefrom and these strips 3 have plugs 4 formed upon their forward ends which fit in the substantially circular recesses 3'. The recesses 2 communicate with

the butt end of the projectile, and in assembling the same, the strips 3 of the relatively 55 soft metal are driven inwardly from the butt ends of the projectile, and when they are completely driven therein, their forward ends are upset and hammered into the recesses 3', to prevent longitudinal movement 60 of the strips during the passage of the projectile through a gun barrel.

Changes in details may be made without 65 parting from the spirit of this invention, but;

We claim:

1. A projectile provided with a plurality of longitudinally extending dove tailed grooves, and strips of relatively soft metal 70 in said grooves and projecting beyond the periphery of the projectile.

2. A projectile provided with a plurality of circumferentially space longitudinally extending grooves, strips of relatively soft metal mounted in said grooves and projecting 75 beyond the outer surface of the projectile, and means to prevent movement of said strips within said grooves.

3. A projectile provided with a plurality of longitudinally extending dove-tailed 80 grooves, strips of relatively soft metal mounted in said grooves and projecting beyond the outer surface of the projectile, and means to prevent longitudinal movement of said strips independent of said projectile. 85

4. A projectile provided with a plurality of longitudinally extending dove-tailed grooves opening at the butt end of the projectile and terminating in sockets near the nose end of the projectile, strips of relatively 90 soft metal positioned in said grooves and projecting beyond the outer surface of the projectile, said strips having their forward ends upset and hammered into said sockets to prevent longitudinal movement of the 95 strips with respect to the projectile.

5. A projectile provided with a plurality of longitudinally extending grooves opening out at the butt end of the projectile and terminating in the nose thereof, metal strips 100 positioned in said grooves and means to prevent the movement of the strips independently of the projectile.

JACOB KUHN.
JOHN A. GUILER.
